UNITED STATES PATENT OFFICE

JAMES C. MILES, OF CLEVELAND, OHIO

HEATING AND VENTILATING APPARATUS

Application filed March 27, 1931. Serial No. 525,728

This invention relates to heating and ventilating apparatus and particularly to that which is adapted for use in connection with hot air heating systems, which are intended to be operated either as a gravity system or as a forced air system. Apparatus of this character usually comprises a fan and damper unit, that is mounted adjacent the inlet conduit of a hot air heating furnace. Normally, the dampers are open when the fan is not in operation so as to provide adequate free area for the passage of air into the heating chamber, but means are provided for automatically closing the dampers when the fan is started. Where the dampers are positioned on each side of the fan, as is shown in my Patent No. 1,508,813 issued September 16, 1924, the blast from the fan is forced directly into the heating chamber without any lateral diffusion. I have found, however, that such lateral diffusion is advantageous, in that it facilitates the movement of air around all parts of the furnace chamber, and also forces it more readily throughout all of the warm air conduits.

a hot air heating furnace, and in Fig. 4 I have shown a heating chamber of a hot air furnace at 10, with an air inlet conduit 11 leading thereto adjacent the lower end thereof. Disposed across the inlet opening of the conduit, I have shown a rectangular frame 12, which is provided with a fan opening 13 and damper opening 14. The fan opening is preferably disposed adjacent the midportion of the frame, while the damper openings are positioned on each side of the fan opening. While my invention may be operated satisfactorily with only one damper opening, nevertheless I prefer to utilize two in order to distribute the air uniformly while it is flowing into the heating chamber under the gravity system. Each damper opening is adapted to be closed by a damper 15, and in the preferred arrangement, the dampers are mounted upon a common shaft 16, which is supported by bearings 17 on the vertical members 20 of the frame.

Each damper preferably comprises a sheet metal piece, which may be bent intermediate to extend around the shaft and rigidly se-

An object of my invention therefore, is to provide an apparatus, which operates automatically and simultaneously with the fan to diffuse the air and to effect positive closure of the dampers when the fan is started. A further object of my invention is to make an apparatus, wherein most of the parts may be made of stampings, and whereby the manufacturing cost of the entire unit may be materially reduced.

Referring now to the drawings, Fig. 1 is a front elevation of a furnace fan unit embodying my invention; Fig. 2 is a section taken on the line 2—2 in Fig. 1; Fig. 3 is an enlarged view of the vane shaft bearing; Fig. 4 is a horizontal section taken through a hot air furnace having my apparatus mounted adjacent the inlet conduit thereof; Fig. 5 is a side elevation of the furnace showing part of the inlet conduit in section; Fig. 6 is an enlarged horizontal section through a part of my device and illustrates the connection between the damper shaft and the actuating vane.

My invention is shown in connection with a furnace, details of which are shown by the drawings.

The shaft as by a link 34 and post 35, and the relationship is such that the vanes extend transversely of the discharge opening when the fan is idle and the dampers are opened. This position is shown in the full lines in Figs. 4 and 5, and by the broken lines 30A in Fig. 6. When the fan is started, however, the current of air flowing therefrom impinges against the vanes and moves them to the full line position in Fig. 6. The same position is also illustrated in Figs. 1 and 2. At such time, the dampers are in the closed position, while the vanes extend obliquely to the air current, wherefore some of the air will be de-

My invention is shown in connection with a reflected laterally, as is shown by the arrows in Fig. 100.

Fig. 2, and forced toward the sides of the conduit 11 and the outside walls of the heating chamber. Thus, the air is diffused within the chamber, and the necessity for the use of baffles therein is obviated.

I claim:

1. In combination, a heating chamber having an air inlet conduit leading thereto, a fan and a damper disposed adjacent the conduit, the damper being mounted upon a horizontal pivot and adapted to be held normally open when the fan is idle, and a vane mounted upon a vertical pivot and disposed on the discharge side of the fan, whereby air from the fan impinges thereon when the fan is in operation, and means for connecting the vane and the damper for moving the damper simultaneously with the vane, and said vane extending obliquely to the current of air from the fan, when the damper is closed, whereby some of the air is deflected laterally as it flows into the heating chamber.

2. In combination, with the heating chamber of a hot air furnace, of an air inlet opening therefor, a fan and a damper disposed adjacent the inlet, said damper being normally open when the fan is idle, and means disposed in the path of the current of air from the fan for moving the damper to closed position when the fan is started, said means extending obliquely and vertically with reference to the current of air whereby some of the air is allowed to flow directly into the chamber while the rest of the air is deflected laterally by said means toward the side of the chamber.

3. In combination with the heating chamber of a hot air furnace, of an air inlet opening therefor, a fan and a damper disposed adjacent the opening, said damper being mounted upon a horizontal pivot and being normally held in open position when the fan is idle, a vane mounted on a vertical pivot within the path of a current of air from the fan, and normally disposed transversely of the path of the air when the damper is open, a link operatively connecting the vane and damper for closing the damper when the fan is started, said link being so connected to the vane that the vane extends obliquely to the path of air when the damper is closed, whereby the vane operates to deflect some of the air laterally into the heating chamber while the fan is in operation.

4. In combination, with the heating chamber of a hot air furnace, of an air inlet conduit leading thereto, a frame extending across the conduit and having two openings therein, a damper positioned adjacent one of the openings, and a fan positioned adjacent the other opening, a horizontally extending shaft attached to the damper and extending across the discharge opening from the fan, a vane mounted on a vertical pivot on the furnace side of said shaft, said vane

being normally disposed transversely of the inlet conduit, and being adapted to be impinged by the air from the fan and moved thereby to an oblique position when the fan is started, and means for operatively connecting the vane to the shaft whereby the vane moves the damper in one direction when the fan is started, and means on the damper for moving it and the vane in the opposite direction when the fan is stopped.

5. In combination with the heating chamber of a hot air furnace, of an air inlet conduit leading thereto, a frame extending across the conduit and having three openings disposed in side by side relationship therein, a fan positioned adjacent the central opening, a damper positioned adjacent each of the side openings, a shaft extending transversely of said openings, a damper rigidly mounted upon said shaft adjacent each of the damper openings, means acting upon the dampers for holding them normally in open position when the fan is idle, a pair of vanes mounted upon vertical pivots within said frame and disposed adjacent the fan opening, said vanes being adapted to extend substantially parallel to the frame when the fan is idle, and said vanes being adapted to be moved to an oblique position with reference to the frame when the fan is started, and means for connecting the vanes to the shaft, whereby the dampers are moved to closed position automatically when the vanes are moved to the oblique position, and said vanes operating when in the oblique position to deflect some of the air toward each side of the conduit, while the fan is in operation.

In testimony whereof, I hereunto affix my signature.
